VENETIAN BLIND

Fred J. Burns, Saginaw, Mich., assignor to The
Columbia Mills, Inc., New York, N. Y.

Application August 28, 1948, Serial No. 46,589

6 Claims. (Cl. 160—177)

1

This invention relates to Venetian blinds adapted to be mounted in a window opening or the like, for controlling the light and air admitted to the room, and more particularly to a slat tilting mechanism for controlling the tilting of the slats.

One of the prime objects of the invention is to provide a very simple, practical, and economical combination saddle and pulley support, composed of a minimum number of parts, all of simple, yet sturdy construction, and which can be readily manufactured and assembled.

Another object is to design an easy-operating tilting mechanism which permits the complete closing of the slats and the elimination of light cracks or rays therethrough, and which maintains the tape spaced apart even when the blind is tilted to either extreme.

Still a further object is to provide a tilt bracket and associated saddle, including means on the saddle for automatically limiting the swinging movement of the tilt bracket.

A further object is to design a tilting mechanism including a saddle of simple, rigid construction, which is suitably shaped and ribbed to reinforce the assembly, and provide upstanding legs on the base sections of the saddle walls for automatically spacing the ladder tape leading to the tilt bracket.

A further object still is to provide a tilting mechanism including a tape tilt bracket and saddle, so arranged and connected that the greater the angle of tilt, the more easy the tilting operation becomes.

Still a further object is to provide a smooth operating, combination saddle and pulley mounting, including spaced-apart walls forming a support and mounting for a pulley and over which the lift cords are trained.

A further object still is to form the upper wall with spaced-apart raised, rolled sections to minimize contacting surface and tape friction as the ladder tape is drawn thereover.

To the accomplishment of the foregoing and related ends, said invention then consists in the means hereinafter more fully described and particularly pointed out in the claims, the annexed drawings and following description setting forth, in detail, certain means and one mode of carrying out the invention, such disclosed means and mode illustrating, however, but one of the various ways in which the principle of the invention may be used.

In the drawings:

Fig. 1 is a fragmentary, front-elevational view

2

of a Venetian blind showing my new tilting mechanism in position therein.

Fig. 2 is an enlarged, transverse-sectional view taken on the line 2—2 of Fig. 1.

Fig. 3 is a view similar to Fig. 2 showing the blind in tilted position.

Fig. 4 is a perspective view of the tilted bracket.

Fig. 5 is a perspective view of the saddle.

Fig. 6 is a side-elevational view of the tilting mechanism.

Referring now more particularly to the drawings in which is shown the preferred embodiment of my invention, and in which the headbox of the blind is indicated by the numeral 9.

15 This headbox is preferably channel-shaped in cross-section, and transversely spaced tape openings 10 and 11 are provided in the bottom wall 12 thereof to accommodate the respective ends 13 and 14 of the ladder tape T as usual, said tape 20 being formed with the usual cross tapes 15 for supporting a plurality of slats 16, which are tilt-20 able to open and/or closed position for the purpose of controlling light and air admitted therethrough, and in a manner to be presently de-25 scribed.

A longitudinally disposed tilt shaft 17 is mounted in bearings 18 provided in the headbox 9, said shaft being actuated by a tilt means C, and comprises a bracket 19 on which the worm 30 and worm shaft 20 and 21 respectively are mounted, said worm having toothed engagement with a small gear 22 which is mounted on the tilt shaft 17 in the usual manner.

The worm shaft 21 is concealed by the front 35 wall 23 of the headbox, and a sheave 24 is mounted thereon, a cord 25 being trained over said sheave, the free ends of the cord hanging within easy reach of an operator, so that the slats may be tilted to any desired position by manipulation 40 of the cords in the conventional manner.

U-shaped tilt brackets B are mounted on the tilt shaft 17 in longitudinally spaced-apart relation, and include legs b which slidably engage the tilt shaft. An elongated, serrated slot 26 is provided in the upper face of each tilt bracket to accommodate the ends 13 and 14 of the ladder tape, and a locking key 27 is insertable in said opening, suitable projections being provided at the ends of the key and project beyond the end of 45 the slot to form a lip 28 so that the keys can be readily removed to release the ends of the ladder tape when desired.

Spaced-apart, preferably stamped saddle mem-55 bers S are mounted in the headbox 9 between the openings 10 and 11 and in horizontal alignment

with the tilt shaft, each saddle being formed as clearly shown in Fig. 5 of the drawings, and comprises vertically disposed connected side walls 29 and 30, the corners 31 of which are rounded as shown to form a smooth surface, and a longitudinally disposed groove 32 is formed in the upper end of the stamping as shown, to reinforce the structure and minimize the surface area over which the ladder tape slides as the slats are tilted.

The lower end sections 33 and 34 of the side walls are bent inwardly as at 35 to accommodate and form a mounting for a roller 36, which is journaled on a pin 37 mounted in the wall sections, and shoulders 38 are formed on the saddle and form stops to limit the swinging movement or travel of the tilt bracket B, preventing excessive lifting of the tilt assembly when it is swung to closed position, and further preventing any binding of the tilt brackets with relation to the saddle.

The lower ends of the wall sections 33 and 34 are bent horizontally to form base sections 39 and 40, and are thence turned upwardly to form legs 41 and 42, the free ends of which are curved as at 43 to form a smooth surface over which the ladder tape rides as the slats are tilted, these leg sections being disposed directly in alignment with or slightly overlying the inner edges of the tape openings 10 and 11 provided in the bottom wall of the headbox, these base sections being clamped or secured to the bottom wall 13 in any desired manner, and I wish to direct attention to the fact that the base sections are longer than the tape openings, thus eliminating pinching or snagging of the tape.

In the assembly of the blind, the ends 13 and 14 of the ladder tape extend upwardly through the openings 10 and 11, thence leading over the upstanding legs 41 and 42, thence over and bearing on the corners 31 of the saddle, and thence being anchored to the tilt bracket B.

Now, when it is desired to tilt the blind slats, the operator grasps the tilt cords 25 and exerts a downward pull on one of the cords to rotate the sheave and worm 24 and 20 respectively, and inasmuch as the worm has toothed engagement with the gear 22, the tilt shaft will be tilted accordingly, this tilting movement swinging the tilt brackets B, so that one set of tapes ride over the legs and rolled sections 41 and 31 respectively, pulling the one set of tapes upwardly, making the other set of tapes slack, so that the slats will be tilted accordingly.

The arrangement and design of the saddle and pulley support insures self-alignment of the tape at all times; the saddle aligns the tilt bracket, and the tilt shaft is freely removable endwise when desired.

The fact that the tapes are spaced apart by the legs 41 and 42 makes for uniform operation, and the degree of tilt also influences the ease of operation. In other words, the operation becomes easier as the blind approaches its tightly closed position, which is contrary to the operation of blinds at present on the market.

From the foregoing description, it will be obvious that I have perfected a very simple, practical, and relatively inexpensive tilt bracket and saddle assembly for Venetian blinds and the like.

What I claim is:

1. A Venetian blind comprising a tilt shaft, tilt brackets in axially spaced relation on said shaft, each bracket including a ladder tape anchoring means on the upper face thereof, with its axis parallel to the tilt shaft axis, and to which the upper ends of the ladder tape are connected, a fixed saddle and tape guard member directly beneath the tilt bracket and formed with vertically disposed, spaced-apart side walls and a continuous arched top section formed with rounded corners over which the tapes slide, and a horizontally disposed groove in said top section, the lower free ends of said walls being outwardly flanged, said flanges terminating in upwardly and inwardly rolled legs forming guides for the ladder tape.
2. The combination defined in claim 1 in which the tilt bracket is horizontally slidable on said tilt shaft and includes spaced-apart legs which straddle each saddle member, and is secured in alignment thereby, and shoulders formed intermediate the length of the side walls for engagement by the tilt bracket to limit the swinging movement of said tilt bracket.
3. The combination defined in claim 1 in which means is provided on the end sections of the side walls of the saddle for limiting the rotative movement of the tilt bracket.
4. The combination set forth in claim 1 in which spaced-apart tape-accommodating openings are provided in the bottom wall of the headbox, and upstanding, inwardly-curved legs on the saddle member and disposed substantially in alignment with the inner edge of the tape openings.
5. A Venetian blind comprising a headbox, a tilt shaft, tilt brackets in axially spaced relation on said shaft, and tape anchoring means on the upper face of said brackets and to which the ladder tape is connected, a stamped saddle member fixedly anchored in said headbox directly beneath said tilt brackets, and comprising an arched top section with spaced apart depending side walls, said top being formed with rounded corners over which the ladder tape slides, and horizontally disposed projecting shoulders on said side walls at a point intermediate their height and engageable by said brackets for limiting the rotative movement of said brackets.
6. The combination defined in claim 5 in which said saddle comprises a one-piece member formed with spaced-apart outwardly projecting base sections terminating in upwardly extending, inwardly curved legs.
